Primary Examiner — Nathan M Johnston(74) *Attorney, Agent, or Firm* — Ira S. Dorman(57) **CLAIM**

The ornamental design for a desiccant dehumidifier, as shown and described.

DESCRIPTION

FIG. 1 is a perspective view of a desiccant dehumidifier showing my new design;

FIG. 2 is a front elevation view thereof;

FIG. 3 is a bottom plan view thereof;

FIG. 4 is a top plan view thereof;

FIG. 5 is a rear elevation view thereof;

FIG. 6 is a left side elevation view thereof; and,

FIG. 7 is a right side elevation view thereof.

The broken lines show portions of the design that form no part of the claimed design.

1 Claim, 7 Drawing Sheets(56)
